DESIGN FOR A SHOE SOLE

Virgil M. Knisely, Lima, Ohio, assignor to Good Cord Rubber Company, Lima, Ohio, a corporation of Ohio

Application April 26, 1947, Serial No. 138,644

Term of patent 14 years

(Cl. D7—5)

To all whom it may concern:

Be it known that I, Virgil M. Knisely, a citizen of the United States, residing at Lima, in the county of Allen and State of Ohio, have invented a new, original, and ornamental Design for a Shoe Sole, of which the following is a specification, reference being had to the accompanying drawing, forming part thereof.

In the drawing:

Fig. 1 is a plan view of a shoe sole, showing my new design; and

Fig. 2 is an edge elevation thereof as viewed from the left of Fig. 1.

I claim:

The ornamental design for a shoe sole, substantially as shown.

VIRGIL M. KNISELY.
